UNITED STATES PATENT OFFICE.

JAMES A. DONNELLY, OF BROOKLYN, NEW YORK.

STEAM-HEATING APPARATUS.

974,245.

Specification of Letters Patent. Patented Nov. 1, 1910.

Application filed May 12, 1906. Serial No. 316,427.

To all whom it may concern:

Be it known that I, JAMES A. DONNELLY, a citizen of the United States, and a resident of Brooklyn, in the county of Kings and State of New York, have invented certain new and useful Improvements in Steam-Heating Apparatus, of which the following is a specification.

My invention relates to fluid circulating or distributing systems such as steam heating systems; and it has for its object to provide a more perfect control and circulation of the circulating medium.

In systems for circulating steam as heretofore constructed, it has been the usual practice to use appliances which serve to pass the air and the water of condensation, but hold back the steam. In the system forming the subject of the present invention, it is my object to effect the removal of the air and the water of condensation by controlling the pressure at which the steam circulates through the various parts of the system. I attain this object by the arrangement and devices set forth in the specification and claims and illustrated in the accompanying drawings in which—

Figure 1 is a diagrammatic view illustrating my invention as applied to a steam heating system. Fig. 2 is a sectional view of one form of trap or valve for the outlets of the radiating devices. Fig. 3 is a sectional view of one form of yielding restricting means. Fig. 4 is a view of a portion of an installation showing a radiator, pipe connections and valves, the latter being in section.

Similar characters of reference designate corresponding parts throughout the several views.

In the drawings, Figs. 1 and 4, I have illustrated my invention as applied to a steam heating system. 10 indicates the steam supply main taken from the exhaust of an engine or other device; or as live steam from a boiler or the like. 11 is the return main leading into the vacuum pump 12; or, in the case of live steam furnished to the steam main 10, if desired into a hot well, feed water heater or simply exhausting into the atmosphere. The return main is used where it is desirable to bring back the water of condensation; and when it is not desirable to do this, the said return main may be dispensed with; and in some cases also the branch returns 18 with their valves

19. 13 are the branch supply pipes connected with the supply main 10 and feed, through ordinary inlet valves 30, heating groups 14, which latter comprise a number 60 of radiators 15 provided with the usual inlet valves 16. At the outlet of each of said radiators is a steam trap, automatic valve or the like, or a valve such as a weighted yielding valve device 17, shown in detail in Fig. 2 and hereinafter more fully described. 18 are the branch return pipes connecting the heating groups 14 to the return main 11. Into each of these branch return pipes 18 there may be inserted a safety valve, check 70 valve, or yielding retarding or restricting means 19, as the valve device shown in Fig. 3. The said valve device 19 comprises essentially a valve body 20 forming a casing; a valve piece 21 seated upon the valve seat 75 22 and suitably weighted with weights 23; a valve passage 24 adapted to be automatically sealed or opened by said valve piece 21; and an inlet 25 and outlet 26 to said valve body 20.

I prefer to make the valve device or trap 17 somewhat similar to the valve device 19, but hinge the valve piece 21 to a separate inclosing casing 27 within the valve body, the said valve piece projecting through the opening or valve passage 24 therein. I may of course substitute one form of valve device for the other; but prefer to use the form of valve shown in Fig. 2 at the outlet of the radiating devices 15, and the form shown in Fig. 3 in the branch returns 18. The valves are in effect weighted check valves acting as pressure reducing valves. I make the valve piece 21 by preference conical, as shown, and projecting into said valve passage 24 so that as the valve piece 21 moves inwardly or outwardly the actual area of passage is correspondingly varied—an increased area of opening being offered with increasing differences of pressure between the two sides 100 of said valve piece, and vice versa. I may provide the said valve piece with an impact surface 28 to aid in the removal of condensed water. I may also provide the valve with a slight leakage opening 24' (Fig. 3) 105 to more quickly permit of the removal of the air in starting and to allow the water to drain out when the system is shut down.

The operation of my system is as follows: Let it be assumed that steam is supplied to the radiating devices 15 through the supply main 10 and branch supply pipes 13 and

inlet valves 30 at atmospheric pressure; and that a vacuum of 10 inches of mercury, that is, a pressure of 10 pounds absolute, is maintained in the return main 11 by a suitable 5 vacuum pump 12. There is thus a difference in pressure of 5 pounds between the steam supply and return. The valves 17 at the outlets of the radiating devices 15 are so weighted as to open only when there exists 10 a difference of pressure of 1 pound between their inlet and outlet sides. A vacuum of 2 inches of mercury, that is, 14 pounds absolute, must therefore exist in the part beyond the outlets before the said valves can 15 open. These branch returns 18 are provided with valves 19 but which are set to open only under a difference of pressure of 4 pounds. A pressure of 14 pounds absolute must therefore exist in the part of the 20 branch returns between the two said valves before the valve 17 will open, and a pressure of 10 pounds in the part beyond the valves 19 before these will open under the conditions stated. The valves 19 thus maintain 25 a part of the branch return portions of the system at the predetermined amount below the inlet or supply pressures to the radiators 15. A positive flow is thus established and maintained from each radiating 30 device in sufficient quantity to effect the removal of the air and the water of condensation. A constant difference of pressure may be thus maintained between the inlet and outlet sides of the valves 17 and 19 serving 35 thereby to determine the maximum flow to the returns. The proper size of the return and of the vacuum pump may therefore be readily calculated, the maximum flow into the fluid return being known. Should the 40 pressure in the portion of the branch returns up to the valves 19 become lower than 14 pounds absolute because of the turning off of most of the radiating devices of a heating group, the valve 19 will remain 45 closed holding back the pressure until it again rises to 14 pounds absolute. Although for the sake of explanation, it has been assumed that a pressure of 15 pounds absolute exists throughout the supply, and 10 50 pounds absolute throughout the return, yet in practice these pressures will not actually exist or be maintained exactly as set forth: For example, the supply pressure at a group at the farther end of the system will be less 55 than at a group nearer the initial supply, and likewise there will be less vacuum at a point at the farther end of the system than at a group near the vacuum pump. Because of this the valves 19 may be differently 60 weighted to allow for the different conditions; the valve 17, however, being usually weighted the same throughout. The vacuum pump, when employed, is designed to handle the maximum quantity of water and 65 air which could possibly be present in the

return; and the only effect of shutting off a number of groups is to cause fluid to be drawn faster through the active groups. Owing to the construction of these valves with a yielding piece, the condensed water 70 is readily discharged; and if they do not open because of insufficient difference of steam pressure, they will nevertheless open due to the head of the condensed water—the opening increasing with increased head 75 or difference of pressure and vice versa. The impact surface 28 also serves to increase the opening when the valve is discharging the condensed water. These weighted yielding valve pieces readily adapt themselves to 80 the varying conditions of pressure existing in the system, control the flow and afford a convenient and perfect means of drainage for the water of condensation. Also, they may be so proportioned to each other and 85 to the pressure of the steam, that a positive predetermined and proportionate flow is established and maintained from each radiating device through the return.

I claim:—

1. In a steam heating system: a steam supply main and a return main; a plurality of heat distributing systems in communication therewith, and each comprising one or more radiating devices; branch supply pipes 95 to and branch return pipes from said heat distributing systems; and weighted means at the outlet of each of said radiating devices as well as in the branch returns, adjusted to permit a predetermined, proportionate flow of steam from each of said radiating devices as well as from each heat distributing system.

2. In a steam heating system: a steam supply main and a return main; a plurality of heat distributing systems in communication therewith, and each comprising one or more radiating devices; branch supply pipes to and branch return pipes from said heat distributing systems; and weighted means at the outlet of each of said radiating devices as well as in each of said branch returns, adjusted to permit a predetermined, proportionate flow of steam from each of 105 said radiating devices as well as from each heat distributing system, and in quantities 110 at least sufficient to effect the removal of the air and the water of condensation from the radiating devices.

3. In a steam heating system: a steam supply main and a return main; a plurality of heat distributing systems in communication therewith, and each comprising one or more radiating devices; branch supply pipes to and branch return pipes from said heat distributing systems; and weighted automatic valves at the outlet of each of said radiating devices as well as in each of said branch returns, adjusted to permit a predetermined, proportionate flow of steam from 115 120 125 130

each of said radiating devices as well as from each heat distributing system, and in quantities at least sufficient to effect the removal of the air and the water of condensation from the radiating devices.

4. In a steam heating system: a steam supply main and a return main; a plurality of heat distributing systems in communication therewith, and each comprising one or more radiating devices; branch supply pipes to and branch return pipes from said heat distributing systems; and weighted automatic valves at the outlet of each of said radiating devices and weighted check valves in each of said branch returns, said valves being adjusted to permit a predetermined, proportionate flow of steam from each of said radiating devices as well as from each heat distributing system, and in quantities at least sufficient to effect the removal of the air and the water of condensation from the radiating devices.

5. In a steam heating system: a steam

supply main and a return main; a plurality of heat distributing systems in communication therewith, and each comprising one or more radiating devices; branch supply pipes to and branch return pipes from said heat distributing systems; and weighted check valves at the outlet of each of said radiating devices as well as in each of said branch returns adjusted to permit a predetermined, proportionate flow of steam from each of said radiating devices as well as from each heat distributing system, and in quantities at least sufficient to effect the removal of the air and the water of condensation from the radiating devices.

Signed at New York, in the county of New York, and State of New York this 11th day of May.

JAMES A. DONNELLY.
